1. This invention relates to a children's gliding teeter and more particularly to a safety swing comprising a plurality of dual units.

UNITED STATES PATENT OFFICE

2,517,207

CHILD'S GLIDING TEETER

Alfred F. Hugueny, Los Angeles, Calif.

Application September 23, 1947, Serial No. 775,712

7 Claims. (Cl. 155—62)

1

This invention relates to a children's gliding teeter and more particularly to a safety swing comprising a plurality of dual units.

Although numerous swing structures of the class to which this invention pertains have been manufactured and placed on the market, yet there remains room for improving such structures in certain particulars so that they will be more durable and more safely operable.

Accordingly it is an object of the present invention to provide, in a swing structure comprising horizontally spaced apart pairs of legs and an overhead horizontal bar supported by and bridging the space between said pairs of legs, an improved hanger structure rigidly supported upon and above said bar and having end portions at each side of said bar, to which the suspending connections of the swing proper are attached.

Another, and more specific object is to provide for using a channel iron structure to better advantage as a part of a means for supporting the suspending connections of the seat portion of the swing.

Among other objects are: to provide a simplified, more sturdy combination of the seat portions of the swing with the swingable suspending means carried by the overhead portion of the swing structure; and to provide a superior means for vertically adjusting the height of the seat proper of the swing in relation to suitable footrests provided for the occupant thereof.

Other objects, advantages and features of invention will hereinafter appear.

Referring to the accompanying drawing, which illustrates a preferred embodiment of the invention,

Fig. 1 is a perspective view of one end portion of the swing structure, showing one pair of supporting legs, the adjacent end portion of the overhead supporting bar, and one of the dual swing units supported upon said bar by improved means provided by this invention.

Fig. 2 is an enlarged sectional detail taken on the plane of line 2—2 on Fig. 1.

Fig. 3 is a detail, on the scale of Fig. 2, showing in plan, one of the overhead channel shapes from which each swing proper is suspended, parts of said channel shape being broken out in order to contract the size of the view.

Fig. 4 is a fragmental sectional detail on the same scale as Fig. 3, looking at the central fragment of that view from the plane indicated by line 4—4.

Fig. 5 is a detail taken approximately on line

5—5 of Fig. 1, on an enlarged scale, one of the telescoped members being shown in elevation and the other in section.

Fig. 6 is an enlarged vertical section through parts shown in the lower portion of Fig. 1, on line 6—6.

Fig. 7 is a cross sectional detail, taken on line 7—7 of Fig. 1, the scale being enlarged.

Referring in detail to the drawing, in Fig. 1 is shown a pair of supporting legs 10, 10, braced by a horizontal rod 11, the upper end portions of said legs being telescoped into sleeves 12, 12, which at their upper ends are welded to the main, nonrotatable horizontal overhead bar 14, thus completing an A-shaped frame at this end of the general structure, it being understood that there is a twin A-shaped frame at the opposite end of the top bar 14. As best shown in Fig. 5, each sleeve 12 is semi-circularly cut out so as to afford footings for semi-circular welds 13 which securely unite said sleeves with said bar. Said bar 14, shown as a tube, has its ends closed by caps 14a.

One of the dual swing units 15 is fully shown in Fig. 1, where it will be seen that said unit comprises an open-ended channel shaped overhead mounting member 16 having flanges 16a, and which, as shown in Fig. 4 is transversely secured to the top bar 14 by means of a double weld 17 supplemented by a pair of inclined tie plates 18, the lower edges of said tie plates being welded at 19 to the lower portion of the bar 14 and the upper edges of said tie plates (which diverge upwardly from each other) each being welded at 20 to the bottom of said channel shaped member. The flanges 16a have vertical outer sides, but inner sides 16b which diverge from below upwardly, as well shown in Fig. 2. Said channel shaped overhead member may be manufactured in a rapid, inexpensive manner by cutting structural steel channels into the required lengths.

Each unit of the dual seat carrying structure is shown as comprising a pair of parallel strap iron bars 21 the upper portions of which are united by ties 22, and 23 and the lower portions of which are connected to each other by handle bars 24 and foot rest bars 25, these four parts being welded or otherwise secured to the paired seat-suspending bars which they connect.

In order to swingably connect the upper end portions of each pair of bars 21 with the channel member 16 a bolt-like shaft 27 is secured transversely to each end portion of said member in an overlying, contacting relation to the

basal or web portion thereof, the end portions of said shaft projecting through and beyond the side flanges 16a of said member. The aforesaid strap metal bars 21 have their upper end portions swingably connected with said projecting end portions of said shafts 27. By preference and as shown each of the bolt-like shafts 27 has the end thereof opposite to its head diametrically reduced at 28 and screwthreaded throughout its diametrically reduced part, the remaining portion of the shaft being unthreaded, thus providing suitable bearing surfaces for the apertured upper end portions of the seat-suspending strips 21. A nut 29 is screwed down upon the threaded end portion of each shaft 27.

In the lower part of Fig. 1 is shown a dual seat structure including the pair of elongated seats 30 which axially align with each other and are secured to the upper side of a common tubular mounting bar 31. The external diameter of this tubular bar is equal to the space between the paired seat-suspending strips 21, between which said bar fits, being secured in place by bolts 32 which pass diametrically through the bar. Said paired strips are each provided with a vertical row of apertures 33, the apertures of each row being horizontally opposite to those of the other row, thus providing for mounting at different heights the bolt 32 and seat-carrying bar 31. A nut 34 is screwed onto said bolt to keep it in place. Owing to the bar 31 being tubular rather than rectangular in cross section, it reduces the friction between itself and the suspending strips 21 between which it is fitted. The preferred means for securely mounting the seats 30 upon the bar 31 is shown in detail in Fig. 7 where a metal strap 35 is shown extending along and resting upon an end portion of the bar 31 and secured to said bar by welds 36. Said metal strap is suitably apertured to receive screw bolts 37 having at their upper ends heads 38 countersunk into the upper surface of the seat, the lower ends of these screw bolts carrying nuts 39.

Referring further to certain details of construction, holes 16c in the flanges 16a are drilled oversize and in such a manner so as to remove a portion of the web of the channel 16, as indicated at 16d, in order that the body portion of the bolt 27 may rest upon the web of the channel. This construction removes a shearing action on the bolt by the flange when a load is applied to the bars 21. Ties 21a attached to the bars 21 opposite the handles 24 are added to further stiffen the bars 21 near their lower ends.

The bar 14 comes from the shop with the sleeves 12 and channel 16 welded thereto and with the caps 14a applied to the open ends as a unit. The dual members 15 with the ties 22, 23 and 21a welded in place and with the handle bars 24 and foot rests 25 applied as shown, come from the shop as a second unit. The mounting bar 31 with the detachably applied seat 30 form another separate unit as do also the legs 10 and horizontal braces 11.

Therefore, in erecting the swing it is only necessary to bolt the several units together, where necessary, and then telescope the sleeves 12 over the upper end portions of the legs 10 that have been previously secured to the ground by means of the pegs 10a extending through apertured foot flanges secured to the lower ends of the legs 10.

In the operation of the device persons using

the same are safeguarded against any overhead part becoming broken or displaced and then falling down upon them. This safety feature is mainly due to the fact that each of the channel shaped members 16 rests bodily upon the overhead bar 14, so that, even if its welded connection with said bar should break loose and the channel slip endwise till one pair of the seat-suspending strips 21 should engage the overhead bar, nothing would fall down upon the persons occupying the seats 30.

In action the seats 30 glide back and forth in a horizontal relation to the ground surface.

The safety feature embodied in the swing makes it a desirable unit in parks and at home without fear of accident to children using it even though older persons are not present to supervise their activities.

I claim:

20. 1. In a swing structure, comprising legs and an overhead nonrotatable horizontal bar supported by said legs, a horizontal, rigid channel shaped member having its midlength portion resting upon and secured crosswise to said bar 25 with the open side of said member directed upwardly, and a dual seat-carrying structure comprising two suspending members one of which is swingably connected with one end portion of said channel shaped member, the other of said 30 suspending members being pivotally connected with the opposite end portion of said channel shaped member.

2. In a swing structure, comprising legs and an overhead nonrotatable horizontal bar supported by said legs, a horizontal, rigid channel shaped member having its midlength portion resting upon and secured crosswise to said bar with the open side of said member directed upwardly, a shaft transversely overlying and abutting against the web portion of said channel shaped member at each side of said overhead bar, each of said shafts having its end portions projecting beyond the sides of said channel shaped member, and swingable seat carrying means connected with each of the projecting end portions of said shafts, said member being a segment of a structural steel channel.

3. In a swing structure, the combination with an overhead supporting means; of two pairs of 50 parallel adjacent suspending bars having upper end portions swingably connected to said overhead means, a horizontally extending tubular seat-supporting bar extending through the lower portions of both of said pairs of bars, the diameter of said seat-supporting bar bridging the space between each of the paired bars, and a single pair of mounting bolts for said seat-supporting bar passing diametrically therethrough, one of said bolts having end portions passing 60 turnably through one of the pairs of suspending bars and the other of said bolts having end portions passing turnably through the other of said pair of suspending bars.

4. In a swing structure, comprising legs and 65 an overhead nonrotatable horizontal bar supported by said legs, a horizontal, rigid channel shaped member having its midlength portion resting upon and secured crosswise to said bar with the open side of said member directed upwardly, and a dual seat-carrying structure comprising two suspending members one of which is swingably connected with one end portion of said channel shaped member, the other of said suspending members being pivotally connected 70 with the opposite end portion of said channel

shaped member, there being an inclined brace at each side of said overhead bar, the lower end portion of said brace being welded to the lower part of said bar, and the upper portion of said brace being welded to the bottom surface of said channel shaped member.

5. In a swing structure, the combination with an overhead supporting means; of two pairs of parallel adjacent suspending bars having upper end portions swingably connected to said overhead means, a horizontally extending tubular seat-supporting bar extending through the lower portions of both of said pairs of bars, the diameter of said seat-supporting bar bridging the space between each of the paired bars, a single pair of mounting bolts for said seat-supporting bar passing diametrically therethrough, one of said bolts having end portions passing turnably through one of the pairs of suspending bars and the other of said bolts having end portions passing turnably through the other of said pair of suspending bars, a horizontal metal strap extending along one end of and having its mid-width portion resting upon said bar, means securing said strap to said bar in such position, and an elongated seat member secured to said straps in a longitudinal overlying relation thereto.

6. The subject matter of claim 5, and said metal strap being welded to said bar by welds extending along each side of the line of contact of said strap with said bar.

7. In a swing structure, comprising legs and an overhead nonrotatable horizontal bar supported by said legs, a horizontal, rigid channel shaped member having its midlength portion resting upon and secured crosswise to said bar with the open side of said member directed upwardly, a dual seat-carrying structure comprising two suspending members one of which is swingably connected with one end portion of said channel shaped member, the other of said suspending members being pivotally connected with the opposite end portion of said channel shaped member, and additional securing means extending from the lower side of said bar to portions of said member spaced away from said bar.
